UNITED STATES PATENT OFFICE.

RAYMOND SCHELIGA, OF HAWTHORNE, CALIFORNIA.

AUXILIARY HEATER FOR BOILERS.

Application filed June 4, 1925. Serial No. 35,028.

This invention relates to improvements in auxiliary heaters for boilers.

An object of the invention is to provide an improved auxiliary heater of improved construction which can be readily applied to boilers of conventional form. In the conventional construction and mounting of return tubular boilers, an arched brick work is employed between the back wall of the mounting and the rear end of the boiler. This arched brick work frequently becomes burned and requires replacement. The auxiliary heater is adapted to occupy the position generally occupied by this arched brick work when applied to a return tubular boiler. The improved auxiliary heater can be applied to other types of boilers, as will be hereinafter described.

With the foregoing and other objects in view which will be made manifest in the following detailed description and specifically pointed out in the appended claim, reference is had to the accompanying drawings for an illustrative embodiment of the invention, wherein:

Figure 1 is a side elevational view illustrating the improved auxiliary heater in applied position and as associated with a return tubular boiler of conventional construction, and

Fig. 2 is a transverse sectional view of the improved auxiliary heater.

Referring to the accompanying drawings wherein similar reference characters designate similar parts throughout, the improved heater consists of a plurality of tubes 10, each of which has its ends provided with heads 11, over which the end edges 12 of the tubes are crimped. The tubes 10 are arranged side by side with their sides contacting with each other. A conduit 13 is connected to the heater through one of the heads 11 of an end tube. The tubes are connected to each other as by connections 14 which are connected by couplings or unions 15, although any other suitable means for connecting the tubes together can be employed. As will be noted from Fig. 2, each of the intermediate tubes is so arranged that one of its ends or heads is connected to the adjacent tube on one side, and the opposite head is connected to the adjacent tube on the opposite side. A conduit 16 is connected to the other end tube 10. It will be readily appreciated that fluid flow from the con-

duit 16 to the conduit 13 must necessarily pass through all of the tubes 10.

In Fig. 1 the auxiliary heater is illustrated as mounted upon the rear wall 17 of the boiler mounting and spans the space between the rear wall 17 and the rear end 18 of the boiler. This space is usually occupied by an arched brick work which is conventional and which must be replaced from time to time. The conduits 13 and 16 are not illustrated as connected to any particular part for the reason that they may be connected in several different manners. The auxiliary heater may be employed as a super-heater in connection with the boiler with the conduit 13 connected to the steam dome of the boiler and the conduit 16 leading from the heater to the location where the steam is to be used. In such instances the steam passes from the boiler and through the tubes 10, where it becomes super-heated before passing through the conduit 16. The auxiliary heater can also be employed as a water heater for heating the water before it is admitted to the boiler, in which case either the conduit 13 or 16 can be connected to the source of water supply, and the other conduit may lead toward the feed water pump. The auxiliary heater can also be employed for providing an additional steam space for the boiler, in which instance the conduit 13 is connected to the steam dome or to the steam space within the boiler and the conduit 16 is connected to the water space within the boiler, thus affording additional interior heating surface for the boiler. It will be, of course, appreciated that the auxiliary heater is in no way limited to the functions as above disclosed, but may serve other purposes, if found desirable. In all events it will be appreciated that either water or steam occupies the interior of the tubes 10.

The hot gases which pass beneath the boiler and then rise between the rear end 18 of the boiler and the back wall 17 strike a water or steam cooled metallic surface before passing forwardly through the return tubes in the boiler. Heretofore when the arched brick work has been employed, the brick work becomes burned in the course of time and requires replacement. Furthermore, the heat of the hot gases is lost by the brick work. By employing the improved heater instead of the arch, a water cooled arch is provided, which will not easily burn,

and which uses or utilizes the heat which has heretofore been lost. It will be readily appreciated that by positioning the tubes 10 side by side, a flame-proof arch or wall is provided. It is not necessary to otherwise seal the arch so formed, but if desired, a coating of fire clay, as indicated at 19, may be applied, so as to prevent any escape of gases or flame between the tubes 10. It is, of course, understood that in the course of time, the under surface of the tubes 10 may become burned. In such cases the tubes may be detached from each other and turned over so as to present new surfaces which are not burned.

The application of the improved heater is in no way limited to the particular construction of boiler as shown. It can also be employed in the fire box of the so-called fire box boiler and may serve similar functions to those above described. In such boiler constructions which have the so-called Dutch ovens located forwardly of the forward end

of the boiler, the auxiliary heater can also be employed beneath the roof of the Dutch oven to utilize the heat which is otherwise lost.

It will be understood that various changes in the detail of construction may be made without departing from the spirit or scope of the invention as defined by the appended claim.

I claim:

An auxiliary heater for boilers comprising large headed tubes of equal length fitting closely together side by side, L-shaped pipes fixed in corresponding ends of adjacent tubes, unions connecting the pipes together to connect the tubes together serially, an inlet pipe connected to one outside tube at the opposite end from its union, and an outlet pipe connected to the other outside tube at the opposite end from its union.

In testimony whereof I have signed my name to this specification.

RAYMOND SCHELIGA.
